UNITED STATES PATENT OFFICE

JOHN W. FITZGERALD, OF BOSTON, MASSACHUSETTS

ENVELOPE LOCK

Application filed January 26, 1929. Serial No. 335,344.

This invention relates to improvements in envelope locks.

A prime object of this invention is to provide an envelope lock having the minimum number of parts, thereby greatly decreasing the expense of manufacturing, as well as increasing the efficiency of the device.

A further object of this invention is to provide an envelope lock comprising a receiving member, a cooperating locking element, the receiving member having a plurality of resilient inwardly projecting portions for receiving the cooperating locking element in firm, clamped and interlocked relationship therewith, the resilient, inwardly projecting portions having razor edges adjacent the cooperating element, the space between the resilient, inwardly projecting portions increasing rearwardly, thereby providing more positive and greater holding power between the razor like edges and the cooperating locking element.

Other objects of this invention will appear from the following detailed description of the device, and as disclosed in the single sheet of drawings which is herewith made a part of this application.

In the drawings—

Figure 1 illustrates a plan view of the envelope lock according to this invention.

Figure 2 represents a perspective view of the envelope lock disclosing the two main portions in detached relationship.

Figure 3 illustrates a plan view of the receiving member of the envelope lock.

Figure 4 represents a vertical sectional view of the envelope lock, just previous to bringing the two members of the fastener into interlocked relationship.

Figure 5 illustrates a vertical sectional view of the envelope lock disclosing the cooperating fastening element being brought into interlocked relationship with the receiving member.

Figure 6 represents a vertical sectional view of the envelope lock disclosing the two portions thereof in interlocked relationship.

Figure 7 illustrates a plan view of the envelope lock disclosing the two portions thereof in interlocked relationship.

As one modification of this invention, it is preferred that numeral 1 designate an envelope of the ordinary type, and numeral 2 its flap, adapted to be held in closed relationship to each other by means of an envelope lock, comprising a receiving member 3, made from any suitable material, and formed by stamping or otherwise from a single piece, thereby greatly reducing the expense of manufacturing, a cooperating locking element 4 also formed of a single piece of material.

The receiving member 3 is formed having outwardly extending prongs 5 adapted to clamp firmly in position on the main body 65 portion 1 of the envelope, while the fastening element 4 is provided with prongs 6, adapted to hold the flap portion 2 of the envelope in interlocked relationship with the fastening element 4.

The receiving member 3 is provided with a countersunk portion comprising a plurality of inwardly extending sections 7, having razor like edges 8 along the inner periphery thereof. From this construction it is apparent 75 that when the shank portion 9 of the cooperating fastening element 4 extends through the opening 10 in the receiving member 3, the razor like edges 8 will contact with the shank portion 9, owing to the resiliency of 80 the inwardly extending sections 7, and the cap portion 11 of the shank 9 will be located above and overhang the razor like edges 8, in such a manner that the holding power between the two members 3 and 4 will increase as the 85 attempt to separate them increases.

The countersunk portion of the member 3, according to this invention, is formed in such a manner that the razor like edges 8 will not tend to be affected materially under strain, 90 the flexibility of the inwardly extending sections 7 depending upon the increasing space or openings 12 between the sections 7, as clearly disclosed in Figure 7, wherein the space 12 at or near the base of the sections 7 is considerably wider than the space between the sections at the razor edges thereof.

This invention provides a very efficient and inexpensive envelope fastener. The razor or feather edge on the inwardly extending sec- 100

tions contact in a very efficient manner with the shank portion of the cooperating fastening element, and it has been found from experiment that the rearwardly increased opening between the inwardly projecting sections of the receiving member tends to provide a desired flexibility for firmly clamping the razor like edges to the shank portion.

It will be understood that many changes and modifications may be made in the form of embodiment of the invention within the scope of the following claim without departing from the spirit thereof.

What I claim is:

15 A locking fastener for envelopes comprising a receiver made of a single piece of stamped sheet material and having a flat annular outer portion with prongs on its outer periphery and an inner annular portion
20 curved first upwardly and inwardly from the inner periphery of the outer annular portion, then downwardly and inwardly, and finally upwardly and inwardly, forming two concentric, reversely extending corrugations, the
25 inner portion of the material having a knife edge, and said inner portion having narrow radial slots with parallel walls adjacent the knife edge to form extended knife edge bearing surfaces, said slots terminating in enlarged rounded openings extending into the lower portion of the intermediate inclined portion, in combination with a cooperating
30 fastening element having a headed shank.

In testimony whereof I affix my signature.

JOHN W. FITZGERALD.
